UNITED STATES PATENT OFFICE.

PETER W. MOSHER, OF STOCKTON, CALIFORNIA, ASSIGNOR OF ONE-FOURTH TO
HORACE G. LEARNED, OF STOCKTON, CALIFORNIA.

ELECTRIC ALARM AND AUTOMATIC BRAKE-SET FOR RAILWAYS

1,119,306.

Specification of Letters Patent.

Patented Dec. 1, 1914.

Application filed September 5, 1912. Serial No. 718,645.

To all whom it may concern:

Be it known that I, PETER W. MOSHER, a citizen of the United States, residing at Stockton, in the county of San Joaquin, State of California, have invented certain new and useful Improvements in Electric Alarms and Automatic Brake-Sets for Railways; and I do declare the following to be a full, clear, and exact description of the same, such as will enable others skilled in the art to which it appertains to make and use the same, reference being had to the accompanying drawings, and to the characters of reference marked thereon which form a part of this application.

This invention relates to improvements in railway equipment and particularly for means for giving an alarm when two trains are approaching each other and also to give an alarm when a train is approaching an open switch which is not supposed to be open.

The invention also embodies the application of the structure to a hand car or to an inspection car in such a way or manner as to permit the operators of such cars to determine whether or not a train is approaching from any direction in a manner likely to cause a collision which would result in loss of life or other injury.

The invention further embodies the application of the alarm means to the caboose of a freight train in such a manner as to permit any person in the caboose to determine whether or not a train is approaching from the rear and also should the caboose break loose from the main train to permit a signal to be given to the locomotive of the train whereby the engineer will be apprised of the fact that the caboose has broken loose and he will be able to return and again pick the same up.

The invention further embodies a means for automatically setting the brakes on the train line at any time when any of the above conditions exist thereby compelling the engineer to give attention to his train under dangerous conditions. This brake setting mechanism may or may not be used at the option of the engineer, and its use or non-use would not in any event interfere with the alarm system which constitutes the main gist of the invention.

The main object of the invention is to

produce an electrically operated means for giving the alarms above mentioned, said means consisting in a third rail of any suitable structure or any overhead trolley or any other suitable electrical transmitting means whereby electric power may be transmitted from one train to the other or from a train to a hand car or inspection car or from a train to a caboose and when such connection is made operating an alarm mechanism whereby when any of the above mentioned conditions exist the persons in charge of the trains, hand car, inspection car, caboose or other rolling stock may be apprised of the dangerous condition existing and take steps to avoid the same.

A further object of the invention is to produce a simple and inexpensive device and yet one which will be exceedingly effective for the purposes for which it is designed.

These objects, I accomplish by means of such structure and relative arrangement of parts as will fully appear by a perusal of the following specification and claims.

In the drawings similar characters of reference indicate corresponding parts in the several views.

Figure 1 is a top plan view of a railway showing an outline of a locomotive carrying my improved signal mechanism. Fig. 2 is a side elevation of an outline showing my improved alarm mechanism and automatic brake setting mechanism thereon. Fig. 3 is a top plan view of a switch mechanism showing the application of my alarm system thereon. Fig. 4 is a detailed view of the automatic brake setting mechanism. Fig. 5 is a side elevation of a hand car showing the application of the alarm mechanism thereto. Fig. 6 is a side elevation of a caboose showing the application of the alarm mechanism thereto. Fig. 7 is a side elevation of the subject matter shown in Fig. 4.

Referring now more particularly to the characters of reference on the drawings, the numeral 1 designates the rails of a railway and 2 a third rail constructed in the ordinary manner or of special construction such as a wooden rail with a metal band along the top or in fact any structure found desirable, (or if desired an overhead trolley wire may be used in this connection if found most desirable). This third rail is divided into a series of sections of pre-determined

length separated at certain points as at 3, at which points, the said rails would overlap each other and run parallel with each other a desired distance for a purpose as will appear.

In the cab of each engine I locate a storage or other suitable batteries 4 connected by a wire 24 with a spring pressed shoe 6 or a wheel brush or any suitable contacting means found desirable which shoe contacts with one of the axles 7 of the locomotive or tender which will make a connection through any part of the locomotive with the rails 1. Said batteries 4 are also connected by means of a wire 8 with an alarm bell 9 and with an electric light 10. There is then another wire 12 extending from the bell 9 and light 10 to a spring pressed shoe 13 or in place of said shoe a wheel or brush or other suitable contacting means suitably mounted on the frame of the locomotive or tender and adapted to ride on the member 3 as will appear. The wire 12 in passing from the bell 9 and light 10 to the shoe 13 is connected at any suitable intermediate point with a reversible motor 14 having a shaft 15 on which is a crank 16 projecting through a slot 17 on the end of a rod 18 having a hook 19 or other fastening means adapted to engage a flexibly mounted eye 20 on the air brake lever 21 in the engineer's cab. The wire 12 is then connected with an electromagnet 22 mounted in alignment with the rod 18.

In practice when the two locomotives get on one of the sections of the member 2 at the same time, then a circuit is completed from one of the batteries 4 through the wire 24, shoe 6, axle 7, the wheels of the locomotive, rails 1, the wheels of the other locomotive, the axle 7 of the other locomotive, the shoe 6 of such other locomotive, batteries 4 of the other locomotive, wire 8 of the other locomotive, light 10 and bell 9 of such other locomotive, wire 12, motor 14, electromagnet 22 of such other locomotive, thence along the wire 12 again of such other locomotive to the shoe 13 of the same, thence along the third rail 2 and through the shoe 13 of the first named locomotive, thence through the wire 12 and the members 22, 14, 9 and 10 of said first named locomotive to the batteries of said first named locomotive. This entire completion of the circuit then causes the bells in both locomotives to ring and both lights to be lighted, thus giving a visible and audible alarm to the engineer and fireman or both.

With the above completion of the circuit the motors 15 of both locomotives would be operated to drive the cranks 16 and also the electromagnets 22 would be charged with the electrical energy. The operation of the said cranks 16 would then drive the members 18 into contact with the members 22 and the magnetic qualities of such members 22

would then hold the same in such position. The movement of the said rods 18 would then pull on the levers 21 thus setting the air brakes on the car automatically when the danger alarm was given.

In order that two locomotives might not approach each other head on at a point too close to the division of the sections, I provide such sections to overlap each other as shown in Fig. 1 at approximately a quarter of a mile on each side of the division point. Thus a signal will be given to trains approaching head on at a sufficient distance to enable them to be stopped in time to avoid a collision.

Fig. 3 shows a structure whereby when one train is backing onto a siding and has not yet cleared the same, a signal will be given to another train approaching on the same section, which structure is as follows, viz: Just inside of the inner rail 27 of the switch is an auxiliary rail 28, and there is a wire connection from the rails 1 of the main track to the rail 28 as at 29 and another wire connection 30 from the rail 2 to the inner rail 27. As the train leaves the main track and passes onto the switch the flanges of the wheels of the train pass between and contact with the rails 27 and 28 thus completing the circuit through the alarm system of the approaching locomotive giving notice of the fact that the train which is taking the siding has not yet cleared the main track.

Fig. 5 shows a hand car equipped with the same structure as is the locomotive but not provided with the batteries or brake setting mechanism, simply having a make and break button 31 whereby a person on the hand car can touch such button to connect a circuit to ring a bell 32, which circuit would be made through the connection on the locomotive which might be approaching on the same section of the track and will also give the signals in the locomotive and set the brakes as described above. Inspection cars would also be suitably equipped with this same structure.

Fig. 6 shows a caboose provided with a spring pressed shoe, wheel or brush or other contacting means 33 having a suitable lever operating mechanism by which a person in the caboose can contact the member 33 with the rail 2 in order to send a signal to the locomotive of the train to which the caboose is attached, the circuit being made through the rails 1 and rail 2 and the mechanism on the above mentioned locomotive. By means of this structure, if the caboose should break loose from the train, a person in the caboose could make the necessary contact which would give the alarm in the locomotive connected with the train and bring the train to a stop and the engineer could then determine the cause of the alarm.

and the stopping of the train and upon discovering that the caboose was detached could return and pick up the same.

After the circuit made by the coming of two trains into two sections is broken then a spring 36 pulls the rod 18 away from the member 22 to release the brakes; or if the engineer wishes to operate the brake lever 21 independently of the other mechanism he unhooks the member 20 from the hook 19. Also in order to permit the brakes to be set without the operation of the electrical apparatus, the rod 18 is divided into two parts, namely, the part 18 proper and another part 18^a slidable into the member 18^a and into the hole 17 as shown in Fig. 7, there being a spring 36 to maintain such portion 18^a in normal position when the lever 20 is not being operated.

From the foregoing description it will readily be seen that I have produced such a device as substantially fulfills the object of the invention as set forth herein.

While this specification sets forth in detail the present and preferred construction of the device, still in practice such deviations from such detail may be resorted to as do not form a departure from the spirit of the invention.

Having thus described my invention what I claim as new and useful and desire to secure by Letters Patent is:—

1. A device of the character described comprising the combination with a railway, of a contact element disposed along said railway, a locomotive adapted to ride on said railway, means on said locomotive for engaging said contact element, an electrically operated brake setting mechanism on said locomotive, the same comprising an

electromagnet, a rod connected with the brake lever of the locomotive, means for moving said rod into contact with said electromagnet, a source of electrical energy on said locomotive, a wire leading from said source of electrical energy to said electromagnet, a wire leading from said electromagnet to the means on said locomotive for engaging said contact element, and a wire leading from the other pole of said source of electrical energy and having connection with the body of said locomotive, as described.

2. A device of the character described comprising the combination with a railway, of a contact element disposed along said railway, means on such locomotive for engaging said contact element, an electrically operated brake setting mechanism on said locomotive, the same comprising an electromagnet, a rod connected with the brake lever of said locomotive, a motor for moving said rod into contact with said electromagnet, a source of electrical energy on said locomotive, a wire leading from one pole of said source of electrical energy to said motor, from said motor to said electromagnet, from said electromagnet to said means on said locomotive engaging said contact element and a wire leading from the other pole of said source of electrical energy and being connected with the body of said locomotive, as described.

In testimony whereof I affix my signature in presence of two witnesses.

PETER W. MOSHER.
